UNITED STATES PATENT OFFICE.

HUGH P. MERRIMAN, OF NEW BERLIN, NEW YORK.

DESIGN FOR A CURRYCOMB.

SPECIFICATION forming part of Design No. 23,641, dated September 11, 1894.

Application filed July 11, 1894. Serial No. 517,253. Term of patent 14 years.

To all whom it may concern:

Be it known that I, HUGH P. MERRIMAN, a citizen of the United States, residing at New Berlin Center, in the county of Chenango and State of New York, have invented and produced a new and original Design for Currycombs, of which the following is a specification, reference being had to the accompanying drawing, illustrating the same.

The accompanying drawing represents a perspective view of a currycomb embodying my new and original design.

The leading and essential feature of my design resides in making the body of the comb in substantially the form shown in the drawing. The body of the comb is bent to form the parallel sides A, and inclined portions B, and the curved connections C, C'. The inclined portions extend substantially on the

diagonals of an imaginary parallelogram of 28 which the parallel sides A, form two of the sides. These inclined portions B, are united to the parallel sides A by the four curved portions C, and the two curved portions C' unite the converging ends of the inclined diagonal 25 portions B.

Having thus described my invention, what I claim as new, and desire to secure by Letters Patent, is—

The design for a currycomb substantially 30 as shown and described.

In testimony whereof I have hereunto affixed my name in the presence of two witnesses.

HUGH P. MERRIMAN.
